(57) **CLAIM**

The ornamental design for a side release buckle, as shown and described.

DESCRIPTION

FIG. 1 is a top view of the side release buckle showing the new design;

FIG. 2 is a side view thereof;

FIG. 3 is an end view thereof;

FIG. 4 is an opposite end view thereof;

FIG. 5 is a bottom view thereof;

FIG. 6 is a perspective view thereof;

FIG. 7 is an exploded view of the side release buckle shown in FIG. 1;

FIG. 8 is an exploded view of FIG. 2;

FIG. 9 is an exploded view of FIG. 5; and,

FIG. 10 is an exploded perspective of FIG. 6.

The broken line showing of buckle elements is included for the purpose of illustrating environmental matter and forms no part of the claimed design.
